(57) **CLAIM**

The ornamental design for a motorcycle tag relocator bracket, as shown and described.

DESCRIPTION

FIG. 1 is a view showing the positioning of the ornamental design relative to a rear motorcycle assembly which is shown in phantom.

FIG. 2 is a perspective view of my inventive design of FIG. 1.

FIG. 3 is an enlarged front view of my design for a motorcycle tag relocator bracket.

FIG. 4 is an enlarged rear view of thereof.

FIG. 5 is an enlarged right side elevational view thereof.

FIG. 6 is an enlarged left side elevational view thereof.

FIG. 7 is an enlarged top axial plan view of the inventive motorcycle tag relocator bracket; and,

FIG. 8 is an enlarged bottom axial plan view thereof.
